Primary Examiner — Philip S Hyder*Assistant Examiner* — Darlington Ly(74) *Attorney, Agent, or Firm* — Kofi Schulterbrandt; Michael P. Leary(57) **CLAIM**

The ornamental design for an insertion tool, as shown and described.

DESCRIPTION

FIG. 1 is top, front and right-side perspective view of an insertion tool showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings illustrate portions of the insertion tool that forms no part of the claimed design.
